UNITED STATES PATENT OFFICE.

WALTER W. DIXON AND HUGO VETTEL, OF OAKLAND, CALIFORNIA, ASSIGNEES, BY
MESNE ASSIGNMENTS, TO F. E. CURNISH, OF SAN LEANDRO, CALIFORNIA.

CONVERTIBLE DESK OR TABLE.

1,247,091.

Specification of Letters Patent. Patented Nov. 20, 1917.

Application filed February 8, 1917. Serial No. 147,365.

To all whom it may concern:

Be it known that we, WALTER W. DIXON and HUGO VETTEL, citizens of the United States, residing at Oakland, in the county 5 of Alameda and State of California, have invented new and useful Improvements in Convertible Desks or Tables, of which the following is a specification.

This invention relates to convertible desks or tables of the type having a hinged lid adapted to form a table top in one position and a raised back for a writing or dressing table in its other position, and a vertically movable false top carried within 10 the table frame and raised by the opening of the hinged lid to a position flush with the top of the frame to form a surface for a writing or dressing table and lowered to concealed position within the frame by the 15 closing of the lid. The invention contemplates the provision of novel and improved operative connections between the lid and false top, simple and improved counterbalancing means for the false top to facilitate 20 the operation of the latter, and means for guiding the top in a vertical direction.

In the accompanying drawings, Figure 1 shows a perspective view of a device embodying our invention in the form of a 25 writing table;

Fig. 2 shows a plan view of the same;

Fig. 3 shows a vertical longitudinal sectional view of the same;

Fig. 4 shows a vertical transverse sectional view of the same, the parts being in 30 opened position;

Fig. 5 shows a similar view of the parts in closed position;

Fig. 6 shows a perspective view of a similar device equipped as a dressing table.

The table may be of any desired form and includes a box frame 10 carried upon 35 legs 11. Within the frame is a vertically movable false top 12 guided by means of downwardly projecting bars 13 working in track-ways formed in the table legs. In lowered position the false top rests on the 40 ends of the table legs and is concealed by the box frame.

Hinged to the rear side of the frame is a 45 lid 14 forming the top of the table when closed. Between the lid and the false top at each end are jointed straps 15 which, when 50 the lid is raised, act to lift the false top to a position flush with the top of the frame,

whereby the lid forms the back of a writing or dressing table and the false top forms the surface of the table. In the raised position the false top is supported by a spring-pressed latch 16 resting beneath the same 60 and releasable by means of a knob 17 projecting through the front side of the frame.

In order that the effort required to raise the top may be lessened, we provide a counterbalancing weight 18 fixed upon one end 65 of an arm 19 which is fulcrumed intermediate upon the rear side of the frame and has a pin 19^a at its other end which latter slidingly engages the false top. The top has a jog 20 to form a recess for the weight, 70 the latter being itself concealed from view.

In the case of a writing desk, the lid may be made in two sections, hinged at 21, so that the outer section may be folded back of the inner section, as shown in Figs. 1, 2 75 and 4.

In Fig. 6 the lid is in one piece and has fixtures 22, such as mirrors and the like, whereby to adapt it to the form required for dressing tables. Other arrangements 80 may be employed as desired. The false top may be fitted with shelves 23, pigeon-holes and the like, as shown in Figs. 1 and 2, or may be left plain, as shown in Fig. 6, depending upon the particular purpose for 85 which it is to be used.

On account of the vertical guide means and the counterbalancing device for the false top, the latter may be easily and conveniently operated by a simple connection 90 in the form of jointed straps between it and the hinged lid, and thus the usual complicated operating connections between these parts may be dispensed with.

Having thus described our invention, 95 what we claim and desire to secure by Letters Patent is:—

1. In a convertible desk or table, a frame, a hinged lid for the frame, a vertically movable false top in the frame, connections between the lid and false top for moving the latter to operative position upon raising of the lid, an arm pivoted intermediate its ends to the rear side of the frame, a weight on one end of the arm, and a lateral pin on the 100 other end of the arm slidingly engaging the under face of the false top adjacent the center of the length of said top.

2. In a convertible desk or table, a frame, a hinged lid for the frame, a vertically mov- 110

- able false top in the frame, connections between the lid and false top for moving the latter to operative position upon raising of the lid, and pivoted weighted means borne by the rear side of the frame and slidingly engaged with said false top adjacent the center of the length thereof to exert constant upward tension thereon.
3. In a convertible desk or table, a frame, a false top vertically movable in the frame, an arm extending longitudinally of said false top and pivoted between its ends to the rear side of the frame, a weight on one end of the arm, means on the other end of the arm to engage the false top adjacent the center of the length of the latter, a hinged lid for the frame, and means connected to the lid and false top for operating the latter by the lid movements.
4. In a convertible desk or table, a frame, a sectional lid for the frame hinged to the latter, means to hingedly connect the lid sections to each other so as to allow the front section to fold and lie vertically with the

rear of the rear section, a vertically movable false top in the frame, and connections between the rear section and the false top for moving the latter to operative position upon raising of the rear section.

5. In a convertible desk or table, a frame, a sectional lid for the frame, a vertically movable false top in the frame, means between the false top and lid whereby upon opening of the lid said false top will be moved to operative position, and means whereby one of the lid sections may be opened to gain access to the interior of the frame and while said false top remains quiescent.

In testimony whereof we have hereunto set our hands in the presence of two subscribing witnesses.

WALTER W. DIXON.
HUGO VETTEL.
